UNITED STATES PATENT OFFICE

CHARLES B. CUSHWA, OF YOUNGSTOWN, OHIO, ASSIGNOR TO THE COMMERCIAL SHEARING AND STAMPING COMPANY, OF YOUNGSTOWN, OHIO, A CORPORATION OF OHIO

LINER PLATE

Application filed August 10, 1932. Serial No. 628,121.

My invention relates to a plate for use in building up linings for tunnels or other tubular structures.

In the past, several different types of liner plates have been employed. Cast iron plates have generally been found to be satisfactory but are objectionable because of their considerable weight and cost. Liner plates formed by pressing from a single steel sheet are generally superior to cast iron plates on a weight and cost basis. In the use of such plates, certain facts have been observed which might swing the balance of advantage in favor of the cast iron plate.

Ordinarily, liner plates are connected end to end to form rings which are placed side by side to form a lining for a tunnel as the bore proceeds. When a tunnel lining of pressed steel plates is subjected to a radial load, there is a tendency for the lining to give. This results from the fact that there must necessarily be a slight zone of curvature between the skin or body of a pressed steel liner plate and the integral flanges bent at substantially right angles thereto to permit connection of adjacent plates. Obviously, it is the resistance of these curved portions of the plates to further bending which resists radial loads on the lining, and naturally, the resistance to further bending of a flange bent from a metal sheet is not very great. It may thus happen that tunnel linings made of pressed sheet steel plates do not have the resistance to radial loads characterizing linings made of cast plates, the abutting edges of which may be provided with sharp square edges which directly transmit circumferentially of the lining all radial stress to which it is subject.

An object of the invention is to provide a tunnel liner plate of pressed sheet steel construction, the turned-down flanges of which at each end of the plate have a greater resistance to bending than the end flanges of present types of plates. The resistance of a tunnel lining of such plates to radial loads, obviously, is greater than that of a lining composed of plates having the ordinary integral down-turned flanges at each end.

In accordance with my invention, I form

corrugations in the end flanges of a liner plate and extend the corrugations continuously throughout the length of the skin or body portion thereof. A series of continuous corrugations thus extend from the edge of one end of the plate radially of the tunnel lining to the skin, circumferentially of the tunnel along the length of the plate to the other end, and thence radially inward to the edge of the flange at that end.

In a modified form of the invention, the end flanges of the liner plate may be flat instead of corrugated but will have their edges deformed in symmetry with the corrugations of the skin which extend from end to end of the plate. According to another modification, the corrugations in the skin terminate short of the ends of the plate and the latter are provided with bracing knees pressed therein during the formation of the plate.

For a complete understanding of the invention, reference is made to the accompanying drawings illustrating a preferred embodiment of the invention and certain modifications thereof.

In the drawings,
Figure 1 is a partial plan view of a pair of liner plates constructed in accordance with the invention, connected together end to end, as in the building up of a ring forming a section of tunnel lining;

Figure 2 is a similar view showing a slightly different type of liner plate;

Figure 3A is a similar view of a still further form of plate;

Figure 3 is a partial sectional view along the plane of line III-III of Figure 2;

Figure 4 is an end view of a liner plate of the general type shown in Figures 1 through 3;

Figure 5 is a sectional view along the line V-V of Figure 4;

Figure 6 is an end view of a further modified form of plate;

Figure 7 is a sectional view along the line VII-VII of Figure 6; and

Figure 8 is a view similar to Figure 5 showing a further modification.

Referring now in detail to the drawings,

the liner plates shown in Figure 1 are of one piece construction, being formed by a pressing operation from a single steel sheet of appropriate gauge. Each liner plate has 5 a skin or body portion 10, end flanges 11 and 12, and side flanges 13 and 14. In the die pressing operation by which the plates are formed from a flat sheet, I provide the skin and end flanges of the finished plate with 10 corrugations 15. The side flanges are flat. These corrugations extend lengthwise of the plate and are continuous from edge to edge thereof, as is more clearly shown in Figure 3. Since the curved intersection 16 between 15 the skin and end walls of each plate is thus provided with a series of corrugations, it is strongly reinforced against further bending at that point. As shown in Figure 1, the two end flanges of each plate are conformable in shape so that the ends of adjacent 20 plates will match properly for connection by bolts 17. The corrugations extend at a small angle to the length of the plate so that an outward bulge on one end flange is 25 in line with an inward bulge on the other. It is obvious that for a proper junction, the two plates must be positioned with the proper ends adjacent. If a plate is reversed from its proper position, it will not make 30 a tight joint but can easily be reversed and connected properly to its neighbor.

Figure 2 illustrates a slightly different form of plate, the ends of which are formed to be similar but not conformable. With 35 the type of plate shown in Figure 2, it is necessary to use two different sets of dies and adjoining plates in any ring must be alternately of different pattern. If the two types of plates are properly alternated, however, there will be no necessity for reversing a plate, since both ends of one type of plate will fit either end of the other type. Since 40 the hills and valleys of the corrugations in the end flanges of the plates shown in Figure 2 are in exact alignment axially of the plate, the skin corrugations extend parallel to the side flanges.

Figure 3A shows a type of plate which fits tightly any similar plate and does not 50 have to be specially positioned relative thereto.

Another form of the invention is shown in Figures 4 and 5. According to this form, a tunnel liner plate 18 has a corrugated skin, 55 19, end flanges 20, and flat side flanges 21. The corrugations in the skin 19, as may be observed in Figure 5, extend to the edges of the end flanges 20 and the latter are distorted in symmetry with the skin corrugations. Since the bend between the skin and the end flange is corrugated, it is thereby strengthened to resist further bending due to radial stress to which the tunnel lining is subject.

60 Figures 6 and 7 illustrate a still further

modification of the invention according to which a liner plate 22, having a skin 23, end flanges 24, and side flanges 25, is provided with corrugations 26 which terminate short of the ends of the plate. Reinforcing knees 70 27 are pressed into the end flanges and provide substantial reinforcement for the latter without interfering with the end to end connection of adjacent plates. This characteristic, of course, is common to all forms 75 of the invention.

Figure 8 shows a form of plate generally similar to that of Figures 4 and 5 except that the corrugations terminate at the end flanges. The latter are flat but are distorted slightly in their plane in conformity 80 with the skin corrugations.

It will be apparent from the foregoing description that the invention provides a liner plate for tunnels or other tubular structures which is characterized by greater resistance to radial stresses than former types of pressed sheet steel liners. I am aware that it has been proposed heretofore to corrugate tunnel liners and other sheet metal articles for the purpose of increasing their rigidity, but I believe I am the first to provide a tunnel liner having an end flange bent up from the skin plate and provided with resistance to bending in addition to that of the bent zone of the metal itself. As previously explained, the increased resistance of the end flanges of the plates to bending produces a considerable increase in the resistance of completed tunnel sections to radial thrusts.

Although I have illustrated and described but a few embodiments of the invention, it will be apparent that it may be otherwise constructed without departing 105 from the scope of the appended claims.

I claim:

1. A liner plate comprising a skin or body portion, bent-up side and end flanges integral therewith, said skin and end flanges being provided with continuous corrugations extending from the edge of one end flange to the edge of the other.

2. A liner plate comprising a skin having integral bent-up end flanges, said skin and end flanges having corrugations extending continuously therealong, the corrugations in the end flanges being bent in the same direction from the neutral plane.

3. In a liner plate, a skin or body portion, integral side and end flanges bent up therefrom, said skin having longitudinal corrugations extending from one end flange to the other, said end flanges being distorted transversely in symmetry with the skin corrugations.

4. A liner plate comprising a skin or body portion having integral side and end flanges bent up therefrom, said side flanges being flat, and said end flanges and skin

130

having continuous corrugations extending longitudinally of the plate.

5. A liner plate comprising a skin or body portion, and side and end flanges integral therewith, said body portion having corrugations extending throughout a part thereof, at least, and corrugations in said end flanges extending around the junction of said last-mentioned flanges and said body

10 portion.

6. A tunnel liner segment comprising a skin plate having side flanges and end flanges, the plate being adapted for joining in end-to-end relation with other similar plates to form a lining course, and stiffening corrugations at the junction of the skin plate and the end flanges, the metal of the plate and flanges being deformed from the general plane thereof to form such corruga-

15 tions.

7. A pressed steel liner segment comprising a skin plate curved in one direction, side and end flanges projecting inwardly from said plate, and stiffening corrugations

25 extending from the plate into said end flanges, the material of the plate and the flanges being deformed inwardly from the general planes of said plates to form said corrugations.

30 In testimony whereof I have hereunto set my hand.

CHARLES B. CUSHWA.
